Primary Examiner — Mary Ann Calabrese*Assistant Examiner* — Harper E Comstock(74) *Attorney, Agent, or Firm* — Bradley J. Shelowitz(57) **CLAIM**

The ornamental design for a shower chair, as shown and described.

DESCRIPTION

FIG. 1 is a front, perspective view of a shower chair in accordance with the present design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines shown in the drawings illustrate portions of the shower chair that form no part of the claimed design.

1 Claim, 6 Drawing Sheets(56)
